UNITED STATES PATENT OFFICE.

WARREN H. FROST, OF LONG BEACH, CALIFORNIA.

ELASTIC MATERIAL.

Application filed November 18, 1925. Serial No. 69,805.

This invention relates to elastic materials and more particularly to an elastic material formed in part by coil springs.

An important object of this invention is 5 to provide a construction in which, while some of the threads of the fabric lie transversely to and upon the springs, said threads will not enter between adjacent coils of the springs and interfere with the 10 traction of said springs. This object is attained by the use of transverse threads or cords of a greater diameter or width than the spacing between adjacent coils when the 15 springs are extended to the limit set for them. The limit of extension of the springs is determined by the length of a longitudinally extending thread or cord.

The longitudinally extending cord may consist of a single thread or of several fine 20 threads twisted together or may consist of relatively narrow tape or other flat strips of fabric or other suitable flexible material. The term "cord" used in this specification may define narrow strips of leather or 25 leather substitutes or the like as well as cotton or silk. Rubber cords may also be used for covering the springs, though such construction is not so advisable because of the rapid deterioration of rubber.

30 The invention may be embodied in one form in which coil springs have their ends connected together by cords. The springs may be arranged in a single longitudinally extending series or there may be a plurality 35 of such series lying side by side. When the material is to be employed for the manufacture of corsets, for example, as many as a hundred series of springs and their connecting cords may be employed. The series 40 of springs with their connecting cords, tapes or other connecting members may constitute a portion of the warp of the material and another portion of the warp may consist of threads or cords lying parallel with 45 and between adjacent springs, and the length of these cords limits the extension of the springs. The series of alternating springs and connecting cords and the cords lying between the springs may be interwoven with filler threads. The material 50 made in this manner may be readily cut in those portions where the longitudinal cords or threads connecting the springs are positioned, thus making it unnecessary to cut 55 the springs themselves.

The accompanying drawings illustrate the invention.

Figure 1 is a broken plan view of a piece of elastic material constructed in accordance with the provisions of this invention. 60

Figure 2 is a transverse section on the line indicated by 2-2, Figure 1.

Figure 3 is an enlarged broken longitudinal section on the line indicated by 3-3, 65 Figure 1.

Figure 4 is a greatly enlarged broken longitudinal section on the line indicated by 4-4, Figure 1.

Figure 5 is an exaggerated perspective view to illustrate the weaving. 70

Figure 6 is a plan view of a fragment of elastic material embodying the invention in a modified form.

Figure 7 is an enlarged fragmental longitudinal section on the line indicated by 7-7, 75 Figure 6.

Figure 8 is an enlarged transverse section on the line indicated by 8-8, Figure 6.

Figure 9 is an enlarged transverse section on the line indicated by 9-9, Figure 6. 80

Figure 10 is an exaggerated perspective view to illustrate the weaving in Fig. 6.

Figure 11 is an exaggerated perspective view to illustrate the weaving of a third modification of the invention. 85

Figure 12 is an exaggerated perspective view to illustrate the weaving of a fourth modification of the invention.

First referring to the form of the invention disclosed in Figures 1 to 5 inclusive, 90 there is provided any desired number, one or more, coil springs 16 and these springs are suitably connected at their opposite ends to anchor pieces 17 formed by strips of fabric or other suitable flexible material. In 95 this instance the opposite ends of the springs 16 are provided with eyes 18 and these eyes are secured by stitching 19 to the anchor pieces 17.

Parallel to the springs 16, between adjacent springs is a longitudinal extending thread, threads, cord or cords 20 which may be formed of any flexible material such, for example, as cotton, silk, leather, leather substitutes, or wire. In the instance shown in 100 Figure 1, there are three cords 20 between each two adjacent springs. The opposite ends of the cords 20 are secured to the anchor pieces 17 in any suitable manner. In 105 this instance, the ends of the cords 20 are 110

sewed through the anchor pieces, as clearly shown in Figure 3. The cords 20 are of sufficiently greater length than the springs 16, when said springs are contracted, so that 5 said cords will be slack at such times, as shown to an exaggerated degree, in Figure 3. The cords 20 are, however, of no greater length than necessary to permit of expansion or extension of the springs less than 10 that at which permanent set of the spring coils will take place.

The springs 16 and cords 20 constitute the warp of the fabric and said fabric also comprises filler threads 21 which are interwoven 15 with the springs 16 and cords 20. The filler threads 21 form a sheath for the springs. It is to be particularly noted that the diameter or width of the threads 21 is greater than the space between adjacent coils of the 20 springs when said springs are extended to as great a length as the cords 20 will permit and thus the threads 21 cannot drop between the adjacent coils of the springs. This is shown to an exaggerated degree in Figure 25 4. The interweaving of the threads 21 with the springs 16 forms pockets 22 in which the springs lie. When the springs are contracted, the filler threads 21 will hide them from view.

30 Now referring more particularly to Figs. 6 to 10 of the drawings, for the modification of the invention therein disclosed, the elements that correspond in function to those described above will be indicated by the 35 same reference characters with the addition of the letter "a." In this instance, the springs 16^a are arranged in a longitudinal series or plurality of series, the springs of each series being connected with one another by a cord or cords 221. The diameter of the cord 221 or combined diameters of the cords 221, when several are used, is approximately the same as that of the spring 16^a, and some of the filler threads 21^a, in 40 this instance, pass over and under the cords 221 the same as others of the filler threads 21^a pass over and under the springs 16^a, thus 45 to give substantially the same appearance of the fabric from end to end thereof.

50 The cords 20^a being interwoven with the filler threads thus anchors the cords 20^a at intervals therealong so that when the material is cut into lengths said cords 20^a will remain anchored.

55 Now referring to the modification illustrated in Fig. 11, the elements that correspond in function to those described for Figs. 1 to 5 will be indicated by the same reference characters, with the addition of 60 the letter "b." In this instance the structure is similar to that illustrated in Figs. 6 to 10 excepting that the spring-connecting cords 221^b, which correspond to the cords 221, are 65 interwoven with the filler threads the same as are the longitudinal or warp threads 20^b

that limit extension of the springs. In other words, during the weaving operation, the filler threads are passed between the cords 221^b. Thus between each two adjacent sets of springs 16^b is a woven fabric, of which the 70 longitudinal or warp threads are indicated at 20^b, 221^b and the filler threads at 21^b.

Now referring to the modification of the invention illustrated in Fig. 12, the elements that function the same as those described in 75 Figs. 1 to 5 are indicated by the same reference characters with the addition of the letter "c." It will be noted that the warp members 20^c, in this instance, are formed of relatively wide tapes, cords or strips of material of rectangular cross section, there being a strip interposed between each two longitudinally extending series of the springs 16^c. These warp members 20^c are interwoven with the filler threads 21^c in the 80 same manner as described for the warp threads 20 and filler threads 21. The advantage of using the strips 20^c in lieu of the threads or cords 20 of circular cross section is that said strips will more satisfactorily 85 overcome the tendency of the extended springs of the different series from drawing together into a narrower band. This tendency is greater when the cords are of circular cross section as said cords may roll 90 upon one another.

I claim:

1. An elastic material comprising a coil spring, means to limit extension of the spring, and a flexible sheath enclosing said 100 spring and having transversely extending members of greater width than the spaces between adjacent coils of the springs when the springs are extended to the limit determined by said means.

2. An elastic material comprising a coil spring, anchor pieces secured to the opposite ends of said spring, a flexible member secured at its opposite ends to the anchor pieces, said member being slack when the 110 spring is contracted, and transversely extending flexible members covering the spring of greater width than the spaces between adjacent coils of the springs when the anchor pieces are separated to the limit 115 determined by the first mentioned member.

3. An elastic material comprising a plurality of coil springs positioned lengthwise of each other, a flexible member extending between the springs and anchored at its 120 ends, and transversely extending flexible members interwoven with the springs and first mentioned members, the first mentioned members being slack when the springs are contracted and the transverse members being wider than the spaces between adjacent coils of the springs when the springs are extended to the limit determined by the first mentioned member.

4. An elastic material comprising a lon- 130

- 5 gitudinal series of coil springs, a flexible member between each two adjacent springs secured at its opposite ends to said springs, means to limit extension of the springs, and 5 a flexible sheath enclosing the springs and flexible members and having transversely extending members of greater width than the spaces between adjacent coils of the springs when the springs are extended to the 10 limit determined by said means.
5. An elastic material comprising a longitudinal series of coil springs, a plurality of flexible members between each two adjacent springs secured at their opposite ends 15 to said springs, means to limit extension of the springs, and a flexible sheath enclosing the springs and flexible members and having transversely extending members of greater width than the spaces between adjacent coils 20 of the springs when the springs are extended to the limit determined by said means, the transverse members being interwoven with the first mentioned members.
6. An elastic material comprising a plurality of longitudinal series of coil springs, a flexible member between each two adjacent springs of each series secured at its opposite ends to said springs, a flexible member extending between each two adjacent 25 series of springs and anchored at its ends, and a flexible sheath enclosing the springs and flexible members and having transversely extending members of greater width than the spaces between adjacent coils 30 of the springs when the springs are extended to the limit determined by the second mentioned member, the transverse members being interwoven with the first and second mentioned members.
- 40 7. An elastic material comprising a longitudinal series of coil springs, a flexible member between each two adjacent springs secured at its opposite ends to said springs, a flexible member extending lengthwise of the springs and first mentioned members and anchored at its ends, and a flexible sheath enclosing the springs and flexible members and having transversely extending members of greater width than the spaces 45 between adjacent coils of the springs when the springs are extended to the limit determined by the second mentioned member, the transverse members being interwoven with the first and second mentioned members.
- 50 8. An elastic material comprising a plurality of coil springs positioned lengthwise of each other, a flexible member of greater width than thickness positioned between the springs and anchored at its ends, said member being slack when the springs are contracted, and transversely extending flexible members covering the springs of greater width than the spaces between adjacent coils of the springs when the springs are extended to the limit determined by the first mentioned member.
- 55 9. An elastic material comprising a plurality of coil springs positioned lengthwise of each other, a flexible member of greater width than thickness positioned between the 60 springs and anchored at its ends, said member being slack when the springs are contracted, and transversely extending flexible members covering the springs of greater width than the spaces between adjacent coils of the springs when the springs are extended to the limit determined by the first mentioned member.
- 65 10. An elastic material comprising a plurality of longitudinal series of coil springs, the series being positioned lengthwise of each other, a flexible member between each two adjacent springs of each series secured at its opposite ends to said springs, a flexible member of greater width than thickness 70 positioned between the springs and anchored at its ends, said member being slack when the springs are contracted, and transversely extending flexible members covering the springs of greater width than the spaces between adjacent coils of the springs when the springs are extended to the limit determined by the first mentioned member.
- 75 11. An elastic material comprising a plurality of longitudinal series of coil springs, the series being positioned lengthwise of each other, a flexible member between each two adjacent springs of each series secured at its opposite ends to said springs, a flexible member extending lengthwise between the 80 springs of different series and between the flexible members associated with the different series of springs, the second mentioned flexible member being slack when the springs are contracted, and transversely extending flexible members covering the springs of greater width than the spaces between adjacent coils of the springs when the springs are extended to the limit determined by the second mentioned member, said second mentioned member being interwoven with the third mentioned members.
- 85 12. An elastic material comprising a plurality of longitudinal series of coil springs, the series being positioned lengthwise of each other, a flexible member between each two adjacent springs of each series secured at its opposite ends to said springs, a flexible member extending lengthwise between the 90 springs of different series and between the flexible members associated with the different series of springs, the second mentioned flexible member being slack when the springs are contracted, and transversely extending flexible members covering the springs of greater width than the spaces between adjacent coils of the springs when the springs are extended to the limit determined by the second mentioned member, said second mentioned member being interwoven with the third mentioned members.
- 95 13. An elastic material comprising a plurality of longitudinal series of coil springs, the series being positioned lengthwise of each other, a flexible member between each two adjacent springs of each series secured at its opposite ends to said springs, a flexible member extending lengthwise between the 100 springs of different series and between the flexible members associated with the different series of springs, the second mentioned flexible member being slack when the springs are contracted, and transversely extending flexible members covering the springs of greater width than the spaces between adjacent coils of the springs when the springs are extended to the limit determined by the second mentioned member, said second mentioned member being interwoven with the third mentioned members.
- 105 14. An elastic material comprising a plurality of longitudinal series of coil springs, the series being positioned lengthwise of each other, a flexible member between each two adjacent springs of each series secured at its opposite ends to said springs, a flexible member extending lengthwise between the 110 springs of different series and between the flexible members associated with the different series of springs, the second mentioned flexible member being slack when the springs are contracted, and transversely extending flexible members covering the springs of greater width than the spaces between adjacent coils of the springs when the springs are extended to the limit determined by the second mentioned member, said second mentioned member being interwoven with the third mentioned members.
- 110 15. An elastic material comprising a plurality of coil springs positioned lengthwise of each other, a flexible member of greater width than thickness positioned between the springs and anchored at its ends, said member being slack when the springs are contracted, and transversely extending flexible members covering the springs of greater width than the spaces between adjacent coils of the springs when the springs are extended to the limit determined by the second mentioned member, said second mentioned member being interwoven with the third mentioned members.

Signed at Los Angeles, Calif., this 5th day of November, 1925.

WARREN H. FROST.
